(57) **CLAIM**

The ornamental design for a food product, as shown and described.

DESCRIPTION

The file of this patent contains at least one drawing executed in color. Copies of this patent with color drawings will be provided by the Office upon request and payment of the necessary fee.

FIG. 1 is a perspective view of a first embodiment of a food product;

FIG. 2 is a top plan view of the food product of FIG. 1;
FIG. 3 is a front elevation view of the food product of FIG. 1, the rear elevation view being identical;

FIG. 4 is a right side elevation view of the food product of FIG. 1, the left side elevation view being identical;

FIG. 5 is a bottom plan view of the food product of FIG. 1;
FIG. 6 is a perspective view of a second embodiment of a food product;

FIG. 7 is a top plan view of the food product of FIG. 6;
FIG. 8 is a front elevation view of the food product of FIG. 6, the rear elevation view being identical;

FIG. 9 is a right side elevation view of the food product of FIG. 6, the left side elevation view being identical; and,
FIG. 10 is a bottom plan view of the food product of FIG. 6.

The evenly-spaced broken lines in FIGS. 1-10 illustrate portions of the food product that form no part of the claimed design. The dash-dot-dash broken lines in FIG. 5 illustrate the boundary of the claimed design which forms no part thereof.
